DESIGN FOR A WATER CLOSET

James M. Teahen, Detroit, Mich.

Application March 19, 1934, Serial No. 51,089

Term of patent 14 years

To all whom it may concern:

Be it known that I, JAMES M. TEAHEN, a citizen of the United States of America, residing at Detroit, in the county of Wayne in the State of Michigan, have invented a new, original, and ornamental Design for a Water Closet, of which the following is a specification, reference being had therein to the accompanying drawing, forming a part thereof, wherein;

Fig. 1 is a perspective view from the side of the water closet showing my new design;

Fig. 2 is a similar view from the front of the closet.

I claim:

The ornamental design for a water closet substantially as shown.

JAMES M. TEAHEN.
